PENCIL SHARPENER

Filed Nov. 5, 1932

UNITED STATES PATENT OFFICE

HERBERT A. MOULTON AND EVELYN L. MOULTON, OF PLYMOUTH, NEW HAMPSHIRE

PENCIL SHARPENER

Application filed November 5, 1932. Serial No. 641,429.

This invention relates to a pencil sharpener adapted to receive one end of a pencil and serve as an eraser holder, and to receive the pointed end of the pencil and serve as a 5 point protector.

The invention is embodied in a pencil sharpener which includes a one-piece cylindrical sheet metal tube having an end portion constituting a pencil socket in which a 10 pencil may be rotated, an opposite end portion constituting an eraser socket, and an intermediate portion originally cylindrical and deformed to provide a knife holding rib projecting outwardly from the intermediate 15 portion, and a sharpening knife fixed in said rib and having a cutting edge projecting into said intermediate portion, the arrangement being such that the knife is adapted to sharpen a pencil rotated in said socket, the 20 rib being formed and arranged to be grasped by digits of a hand holding the sharpener and enable said digits to prevent the turning of the sharpener with the pencil.

Of the accompanying drawing forming a 25 part of this specification,—

Figure 1 is a perspective view showing the cylindrical tube before the deformation of its intermediate portion.

Figure 2 is a plan view, and Figure 3 a 30 side view showing the sharpener and a pencil inserted therein.

Figure 4 is a section on line 4—4 of Figure 2.

Figure 5 is a side view of the sharpener 35 looking toward the side opposite that shown by Figure 3.

Figure 6 is a section on line 6—6 of Figure 2.

Figure 7 is a section on line 7—7 of Figure 2.

Figure 8 is a side view of the sharpening 40 knife.

The same reference characters indicate the same parts in all of the figures.

In making our improved sharpener we 45 provide a one-piece sheet metal tube which is cylindrical from end to end, as shown by Figure 1, a portion of the tube being subsequently deformed as hereinafter described.

In the completed sharpener the tube in-

cludes a cylindrical end portion 12 constituting a socket adapted to receive and permit the rotation of a pencil 13, a cylindrical end portion 14 constituting a socket which may receive an eraser 15, and an intermediate 55 portion 16, coaxial with the end portions, and having an integral deformation constituting a hollow knife-holding rib. Said deformation may be formed by suitable instrumentalities changing the form of a portion 60 of the tube shown by Figure 1 by inwardly displacing opposite sides of the tube as shown by Figure 2, and outwardly displacing other portions of the tube, to form a hollow rib composed of flat parallel sides 17, a 65 longitudinal neck portion 18 connecting the outer portions of the sides 17, and a transverse neck portion 18^a, substantially at right angles with the tube axis, connecting the portions of the sides adjacent the tube portion 70 14.

19 designates a sharpening knife having a back edge seated on the longitudinal rib neck 75 18, a relatively long end edge seated in the transverse neck portion 18^a, flat sides contacting with rib sides 17, and a cutting edge 20 projecting from the rib into the intermediate portion and inclined relative to the tube axis, as shown by Figures 4 and 5.

The rib is obliquely arranged relative to 80 the axis of the tube, and to the axis of a pencil therein. The sides 17 of the rib are tangentially arranged as shown by Figures 6 and 7, so that the knife is tangential to the inserted pencil and adapted to sharpen the 85 same when it is rotated.

The rib is formed and arranged to be 90 grasped by digits 22 of a hand holding the sharpener, to prevent the sharpener from turning with a pencil rotated by the other hand.

The end portion, or pencil socket 12, may be provided with a slot 23 rendering said portion yieldingly expandible, and the tube 95 may be provided with the usual securing clip 24.

An opening 25 for the escape of shavings removed from the pencil by the knife is shown by Figures 5 and 6.

The metal of the tube displaced in form- 100

ing the hollow rib is so disposed that the neck portion 18 is inclined outwardly from its junction with the socket portion 12, as shown by Figures 3, 4 and 5. The back and cutting edge of the approximately triangular knife are oppositely inclined, as shown by Figure 8.

It will be seen that when the back edge and the wider end edge of the knife are seated as described on the longitudinal neck portion 18, and the transverse neck portion 18^a of the rib, the knife is positively supported by said neck portions against force tending to displace it outward from the axis of the tube and endwise toward the socket 14. The knife may therefore be secured in its operative position wholly by the thrust of its back and wider end edges against said neck portions, and by the frictional contact between the sides of the knife and the sides of the rib. The knife may be additionally secured to the rib by solder, or otherwise.

It will also be seen that the device is very simple, its only essential parts being the deformed one-piece tube and the knife.

The seamless tube characterized as shown and described, renders the sharpener strong and durable, the portion of the tube engaging the knife being inexpandable so that the knife cannot be accidentally displaced from its operative position.

We claim:

As an article of manufacture, a two-piece pencil sharpener composed of a seamless sheet metal tube having cylindrical end portions constituting sockets in axial alignment with each other, and an intermediate portion having a deformation constituting a hollow knife-holding rib projecting outward from one side of the axis of the tube, said rib including flat parallel sides tangentially and obliquely arranged relative to the tube axis, a longitudinal neck portion connecting the outer portions of the rib sides and inclined relative to said axis, and a transverse neck portion substantially at right angles with the tube axis, said tube and rib being integral with each other, and a substantially triangular sharpening knife having a back edge seated on the longitudinal neck portion, a relatively wide end edge seated on the transverse neck portion, flat sides bearing on the sides of the rib, and a cutting edge projecting from the rib into the intermediate portion of the tube, the portion of the tube having said rib being inexpandable.

In testimony whereof we have affixed our signatures.

HERBERT A. MOULTON.
EVELYN L. MOULTON.
